UNITED STATES PATENT OFFICE

STEPHEN FAITH, OF CHICAGO, ILLINOIS

DESIGN FOR AN AUTOMOBILE LICENSE-PLATE HOLDER

Application filed November 22, 1929. Serial No. 33,524. Term of patent 7 years.

To all whom it may concern:

Be it known that I, STEPHEN FAITH, a citizen of the United States, residing at Chicago, in the county of Cook and State of Illinois, have invented a new, original, and ornamental Design for an Automobile License-Plate Holder, of which the following is a specification, reference being had to the accompanying sheet of drawing, forming part thereof.

In the drawing, Figure 1 is a front elevational view of an automobile license plate holder, showing my new design; and Figure 2 is a side elevation thereof.

I claim:

The ornamental design for an automobile license plate holder, as shown.

STEPHEN FAITH.
